DESIGN FOR A COMBINED ROASTER AND BROILER OR SIMILAR ARTICLE

George D. Eddy, San Gabriel, Calif.

Application April 21, 1941, Serial No. 100,544

Term of patent 3½ years

To all whom it may concern:

Be it known that I, George D. Eddy, a citizen of the United States and a resident of San Gabriel, county of Los Angeles and State of California, have invented a new, original, and ornamental Design for a Combined Roaster and Broiler or Similar Article, of which the following is a specification, reference being had to the accompanying drawing, forming a part thereof.

Referring to the drawing:

roaster and broiler, or similar article, showing my new design.

I claim:

The ornamental design for a combined roaster and broiler or similar article, substantially as shown.

GEORGE D. EDDY.
